UNITED STATES PATENT OFFICE.

HARRY J. SMITH, OF LAKEWOOD, OHIO, ASSIGNOR TO THE HILL CLUTCH COMPANY, OF CLEVELAND, OHIO, A CORPORATION OF OHIO.

COLLAR-OILING JOURNAL-BOX.

1,160,663.

Specification of Letters Patent.

Patented Nov. 16, 1915.

Application filed August 7, 1908. Serial No. 447,374.

To all whom it may concern:

Be it known that I, HARRY J. SMITH, a citizen of the United States, residing at Lakewood, in the county of Cuyahoga and 5 State of Ohio, have invented a certain new and useful Improvement in Collar-Oiling Journal-Boxes, of which the following is a full, clear, and exact description.

The object of this invention is to provide a 10 cheap and efficient collar-oiling journal-box.

The invention consists of the construction and combinations of parts shown in the drawing and hereinafter described and definitely pointed out in the claim.

15 In the drawing, Figure 1 is a longitudinal vertical section of a journal-box embodying the invention. Fig. 2 is a plan view of the base of said box. Fig. 3 is a plan view of the base of said box when the shaft is 20 mounted thereon and the wipers are in place. Fig. 4 is a transverse sectional view in the plane of line 4—4 on Fig. 1. Fig. 5 is a transverse sectional view in the plane of line 5—5 on Fig. 3. Fig. 6 is a fragmentary 25 section on line 6—6 of Fig. 5. Fig. 7 is a fragmentary section in the plane indicated by line 7—7 on Fig. 2. Fig. 8 is a plan view of one of the wipers. Fig. 9 is a sectional view of said wipers on line 9—9 of Fig. 8; 30 and Fig. 10 is a half end view and half section in the plane of line 10 on Fig. 1.

The journal box consists of two main parts, to wit, the base A and the removable cap B. In the base are two babbitt-lined 35 shaft-bearings C, C; and below them is a cored out oil reservoir a. At the ends of the base are the inwardly turned flanges a' which form the ends of this oil reservoir.

In the cap B are corresponding bearings 40 D, D. Between the bearings C, C, in the base, and between the bearings D, D, in the cap is a groove J which, when the cap is on the box, extends entirely around the shaft G which is rotatably mounted in the described 45 bearings. This annular groove extends into and communicates with the oil reservoir a. An oiling collar F is fixed to this shaft and is nicely fitted in this annular groove, whereby the ends of the bearings by engagement 50 with the sides of the collar serve as thrust bearings for the shaft.

Along the sides of the base are the upwardly extended flanges a', the top edges of which are a considerable distance above the 55 top edges of the bearings C, C. The lower

part of the cap and the bearings D, D, are fitted within the flanges a'; and on the cap are two laterally extended flanges b' which rest upon the tops of the flanges a', and are a considerable distance above the lower edges 60 of the bearings D, D. When the flanges b' of the cap are resting upon the flanges a' of the base, the lower edges of the bearings C, C and cap B do not touch the upper edges 65 of the bearings D, D, and of the base adjacent thereto, but, on the contrary, are such distance apart that oil grooves or channels K are formed between them. Any oil in either of these channels will be in direct contact with the rotating shaft G.

The grooves in the base and cap are so arranged that the lowermost portion of the groove does not extend below the plane of the central part of the bearing. The groove itself is above the central portion of the 75 bearing, and the upwardly extending portions a' of the base are made high so that it is practically impossible for the oil to seep past the junction of the base and the cap.

The oil will be lifted from the reservoir 80 by the collar F. Wipers E are secured within the box in position to wipe oil from the collar and cause it to flow in the adjacent channel K. Two of these wipers are shown, one on each side of the box; and two are 85 used so that the box will be adapted, without change, to be used with the shaft which sometimes turns in one direction and sometimes in the other. Each wiper is notched so as to loosely embrace the collar F. On 90 the inner end of each wiper are downwardly turned legs e which rest upon the upper edges of the bearings C, C. Near the outer end of each wiper is a single downwardly extended lug e' which rests upon a boss a' 95 on the base. This boss and the ribs a' which join it are raised above the level of the channels K. As the shaft rotates oil on the collar F is wiped off. The top of the wiper is inclined inward and in both directions from its middle. Therefore the oil wiped off will flow down the inclined top of the wiper into the channels K. It will be noted that the wiper is not rigidly secured in position, but is permitted a certain amount of movement 100 up and down, as well as sidewise. This, together with the particular placing of the wiper insures that the weight of the wiper will always hold it against the oil ring. The ribs a' adjacent to the annular groove J act 105 110

as barriers preventing the oil discharged into the channels K by the wiper from flowing from them into said annular groove and thence back into the oil reservoir; and other 5 ribs a^7 at the other ends of said channels hold a substantial quantity of oil in the channels. The shaft forms the inner walls of these oil channels, wherefore the shaft is always effectively lubricated.

10 It should be noted that the ends of the bearings C, C and D, D are a little distance away from the end flanges a' , whereby there is formed a groove a^8 in which the excess oil may run from the channels K, K down 15 into the oil reservoir.

On the bottom of the base and on the top of the cap are respectively the bosses a^9 and b^3 which are provided to be engaged by the adjustable supports of a hanger or other device for supporting the described box. On the base at the sides thereof are the bosses a^{10} , which are provided to be engaged by the adjusting device of such hanger or its equivalent for the purpose of moving the 25 box laterally to properly align it. The provision of these aligning bosses on the base only permits the removal of the cap whenever it is desired without disturbing the base.

30 Having described my invention, I claim:
In a journal box, the combination of a base containing two separated shaft bear-

ings and an oil reservoir and having upwardly extended flanges along its sides, which flanges extend above the upper edges 35 of the bearings therein, with a cap containing two separated shaft bearings and having outwardly extended flanges adapted to rest upon the flanges on the base, said parts being constructed so that the distance 40 between the lower edge of the outwardly extended flanges of the cap and the lower edges of the bearings in the cap is less than the distance between the tops of the upwardly extended flanges of the base and the 45 upper edges of the bearings in said base forming longitudinal oil grooves between the opposing edges of the base and cap, an oil lifting collar fixed to the shaft and occupying the annular space between the 50 proximate edges of said bearings, and a wiper having arms upon opposite sides of the said collar, the ends of said arms resting in the oil grooves, and the body of the wiper being pivotally supported by the 55 base, whereby oil lifted by said ring will be wiped therefrom by the wiper and caused to flow into said longitudinal grooves.

In testimony whereof, I hereunto affix my signature in the presence of two witnesses. 60

HARRY J. SMITH.
